UNITED STATES PATENT OFFICE.

JOHN R. SHANNON, OF LOWELL, ARIZONA.

OIL-VAPOR GENERATOR.

Application filed January 14, 1922. Serial No. 529,243.

To all whom it may concern:

Be it known that I, JOHN R. SHANNON, a citizen of the United States, residing at Lowell, in the county of Cochise and State 5 of Arizona, have invented certain new and useful Improvements in Oil-Vapor Generators, of which the following is a specification, reference being had to the accompanying drawings.

10 This invention relates to means for generating vapor from oil, and particularly to means for generating vapor for use in internal combustion engines from crude oil.

The general object of this invention is to 15 provide means which may be easily fitted to and easily placed in association with any internal combustion engine and the carbureter therefor, whereby the exhaust heat from the engine is used for the purpose of vaporizing the crude oil by passing this exhaust heat through a body of the oil contained in what may be termed the boiler and using the vapor thus generated which is under pressure as a means for injecting the mixture of 20 crude oil and water into the boiler or heater.

A further object is to provide means whereby the vapor in the generator may be purified by its passage through the carbureter.

30 Still another object is to provide an improved form of vapor generator in which the boiler or oil container is provided with a plurality of flues extending through the boiler, through which flues the exhaust passes.

Another object is to provide a construction of this character wherein a float valve in an oil tank is used to control the flow of vapor to the injector, whereby the cool oil 40 and water are fed into the boiler or generator.

Still another object is to provide an improved form of regulating valve for controlling the feed of the vapor to the carbureter.

Other objects will appear in the course of the following description.

My invention is illustrated in the accompanying drawings, wherein:—

50 Figure 1 is a vertical longitudinal section of a generator constructed in accordance with my invention, the regulating valve and the carbureter being shown in elevation;

55 Figure 2 is a fragmentary vertical section of the oil and water container showing the float whereby the vapor valve is controlled;

Figure 3 is a longitudinal sectional view of the regulating valve;

Figure 4 is a longitudinal sectional view of the injector;

Figure 5 is a longitudinal sectional view of the check valve controlling flow into the tubular boiler or heater.

Referring to these drawings, 10 designates a casing constituting a boiler or heater 65 closed at its upper and lower ends and through which extend the flues 11 in the usual manner of a fire tube boiler. The space within the casing and surrounding the flues 11 is intended to be filled with crude 70 oil. Above the casing 10 is a substantially conical head 12 into which the upper ends of the flues or fire tubes 11 open, and below the boiler 10 is a head 13 into which the lower ends of the fire tubes 11 open, this 75 head 13 being connected to a fire or exhaust pipe 14. Communicating with the upper end of the head 12 is an exhaust pipe 15 leading from the exhaust of the engine. The contracted mouth of the head 12 where 80 it opens into the exhaust pipe 15 is provided with a valve 16 of any usual or suitable form controlled by a manually operable rod 17 whereby all or any desired proportion of the exhaust gases may be directed 85 into the head 12 and so through the flues 11. When this valve is entirely closed, all of the exhaust gases will pass along the pipe 15 and none of the exhaust gases will be discharged into the head 12 and into the boiler. 90 When the valve is entirely open, of course, all of the exhaust gases will pass through the boiler. The pipe 15 may be considered to be the usual exhaust pipe leading from an internal combustion engine. 95

Disposed to one side of the boiler shell 10 and extending vertically is a tank 18 for heated oil, which is connected by a duct 19 at its lower end to the lower end of the boiler 10 so that the oil within the casing 10 stands at the same level as the oil within the casing 10, except for the fact that there is vapor under pressure in the upper end of the tank 18 which will, to a certain extent, depress the level of the oil in the 100 tank 18.

For the purpose of feeding crude oil and water into the boiler 10, I provide a feed pipe 20 which leads into the boiler, as illustrated in Figure 1, and is provided with a 110 check valve 21, this check valve preventing flow from the boiler 10 into the pipe 20 but

- 2
- permitting flow from the pipe 20 into the boiler 10. The pipe 20, as illustrated in Figure 4, connects with an injector shown as including the two conical nozzles 22 and 23, 5 the nozzle 22 extending into the butt end of the nozzle 23 and the nozzle 23 extending into a pipe section 24 which is coupled to the pipe section 20 by means of a coupling 25. Surrounding the nozzle 22 is a chamber 26, 10 and a relatively small water pipe 27 opens into this chamber 26. The large end of the nozzle 23 is formed with an annular chamber 28 into which an oil pipe 29 opens, this annular chamber having perforations 30 15 opening into the nozzle. The large end of the nozzle 22 is connected by means of a pipe 31 with the upper end of the tank 18, as illustrated in Figure 2. This pipe 31 adjacent its upper end is formed with a valve seat 33, and coacting with this seat is a longitudinally shiftable valve 34 having a stem 35 extending through a suitable stuffing box 36 into the upper end of the tank 18 and being there engaged by a cam-shaped 20 25 30 35 40 45 50 55 60 65 70 75 80 85 90 95 100 105 110 115 120 125 130 135 140 145 150 155 160 165 170 175 180 185 190 crude oil, though I do not wish to be limited to such use, and it permits crude oil to be vaporized and used in internal combustion engines and may be readily used in conjunction with the usual exhaust pipe of a motor car and the usual carburetor. It will be obvious that I have illustrated the general arrangement of the parts in Figure 1 somewhat diagrammatically, as this arrangement 5 may be varied in many ways and, of course, the proportions of the parts may be changed. By the construction, I provide for vaporizing crude oil and water and provide for a forced feed of the oil and water into 10 the boiler against the pressure therein. The oil and water flow preferably by gravity to the pipes 27 and 29 from suitable oil and water tanks. Passing through the injector, the oil and water are thoroughly mixed. Of 15 course, only a very small amount of water is admixed with the oil, just enough to insure perfect combustion. The initial starting of the engine may be secured by using gasoline or other relatively volatile fuel in the 20 usual manner until the exhaust gases traveling through the exhaust pipe 15 are hot enough to vaporize the oil, as before described. At this time the valve 16 may be opened to deflect the hot exhaust gases 25 downward through the head 12, through the pipes or flues 11, and through the head 13 and pipe 14.

I claim:

1. An oil vapor generator of the character 35 described including a boiler, hollow heads disposed at opposite ends of the boiler, fire tubes extending through the boiler and communicating with the interior of said heads, an exhaust pipe connected to one of said 40 heads, a vaporizing coil disposed within the last named head and operatively connected at one end to the upper end of the boiler, a vapor container into which the vapor passes from said coil, a tank operatively connected 45 at its lower end to the lower end of the boiler, a float in the upper end of said tank, an injector connected to a source of oil and discharging into the boiler, means for conducting vapor from the vapor container to 50 the injector, a valve for controlling the flow of vapor to the injector, and a float disposed in said tank closing said valve when the oil level in the tank has risen beyond a predetermined degree and opening said 55 valve upon the lowering of the level below a predetermined degree.

2. A vapor generator of the character 60 described comprising a boiler, fire tubes extending through the boiler, hollow heads in opposite ends of the boiler into which the fire tubes open, an exhaust pipe connected to and discharging into one of said heads, a vaporizing coil connected at one end to the upper end of the boiler and disposed within 65 said last named head, a purifying chamber

into which said coil discharges, a vapor container into which the purifying chamber discharges, a discharge pipe leading from the vapor container and having a controlling valve, an oil tank associated with the boiler 70 and communicating at its lower end therewith whereby the level of oil in the tank and boiler will be approximately the same, a pipe leading from said vapor container into the upper end of the tank, an injector 75 connected to a source of oil and discharging into the boiler, a pipe leading from the upper end of said oil tank to the injector and carrying vapor from the upper end of the oil tank to the injector, a valve controlling the passage of vapor to the injector, and a float disposed in the tank and controlling the movement of the valve. 80

3. A generator of the character described comprising an exhaust heated boiler, an exhaust heated vaporizing coil connected to the boiler, a purifying chamber into the lower end of which the coil discharges and having a series of foraminous trays 85 containing purifying material, a vapor containing chamber into which the purifying chamber discharges, a discharge pipe extending from said chamber, a regulating valve controlling the flow from the discharge pipe, a tank extending parallel to the boiler and 90 communicating at its lower end therewith whereby the level of liquid in the tank is approximately the same as that in the boiler, a vapor pipe leading from the upper end of the vapor container to the upper end of said 100 tank, an injector leading into the boiler and connected to a source of oil and a source of water, a vapor pipe leading from the upper end of the tank above the level of liquid therein and into said injector, a valve 105 controlling the flow through said last named pipe, and a float in the tank controlling the opening of said valve.

4. In an oil vapor generator, a purifying chamber having a series of perforated trays 110 having purifying chemicals thereon, a boiler, means for conducting vapor from the upper end of the boiler into the lower end of the purifying chamber, a vapor collecting chamber into which the purifying chamber discharges, an injector discharging into the boiler and connected to a source of water and oil, means for causing the operation of said injector through the pressure of the vapor within the collecting chamber, and 115 means automatically acting to cause the operation of the injector upon the lowering of the level of oil within the boiler and preventing the operation of the injector upon the predetermined rise in level. 120

5. A vapor generator for internal combustion engines comprising a boiler, hollow heads on the ends of the boiler, fire tubes extending through the boiler and communicating with said heads, an exhaust gas pipe 125

communicating with one of said heads, a valve for controlling the passage of the exhaust gases from said pipe into said last named head, a vaporizing coil disposed in the 5 last named head and connected to the upper end of the boiler, a purifying chamber into which said coil discharges, a vapor containing chamber into which the purifying chamber discharges, a tank associated with the 10 boiler and communicating at its lower end with the lower end of the boiler, a vapor pipe leading from said vapor containing chamber to the upper end of said tank, an injector discharging into the lower end of

the boiler and connected to a source of oil, 15 a vapor pipe leading from the upper end of the tank to said injector, a float in the upper end of the tank, a valve controlling the passage of vapor through the vapor pipe and controlled by said float, a service 20 pipe leading from said vapor container, a regulating valve controlling the passage of vapor from the service pipe, and a carburetor through which the vapor so regulated is discharged

In testimony whereof I hereunto affix my signature.

JOHN R. SHANNON.
